UNITED STATES PATENT OFFICE.

FREDERICK E. CARLSON, OF NEW BRITAIN, CONNECTICUT, ASSIGNOR TO LANDERS, FERRY & CLARK, OF NEW BRITAIN, CONNECTICUT, A CORPORATION OF CONNECTICUT.

OVEN.

1,128,755.

Specification of Letters Patent. Patented Feb. 16, 1915.

Original application filed August 7, 1913, Serial No. 783,475. Divided and this application filed December 4, 1913. Serial No. 804,640.

To all whom it may concern:

Be it known that I, FREDERICK E. CARLSON, a citizen of the United States, and a resident of New Britain, in the county of 5 Hartford, State of Connecticut, have invented certain new and useful Improvements in Ovens, of which the following is a specification.

The invention is concerned with the general mechanical construction of the body 10 of the oven, and with additional features of construction which will be more particularly pointed out in the following specification.

The invention is illustrated in its adaptation to use in an electric oven.

In the drawings—Figure 1 is a front view of an oven embodying my invention. Fig. 2 is a sectional view on the line 2 . . . 2 of Fig. 1. Fig. 3 is a perspective view of 20 the oven with a part of one side wall broken away. Fig. 4 is a detail view of the door construction. Fig. 5 is a sectional view on the line 5 . . . 5 of Fig. 4. Fig. 6 is a detail view showing the construction of the 25 main body of the oven.

Referring first to the mechanical construction of the oven, the main body of the oven, comprising the sides *a*, *b*, and the back *c*, is a double-walled structure formed preferably from a single sheet of thin stock of 30 proper width, which is folded about a form to the proper shape, the ends of the strip being united by an interlocking seam as at *d*. Sheets of asbestos *e* are laid against the 35 inner faces of these walls, and then spacers *f* are inserted to prevent collapse. The top and bottom are formed by fitting within the walls of the body dished plates *g*, *h*, having at their side and rear edges channeled lateral 40 flanges *g'*, *h'*, forming pockets *g'', h''*, into which the top and bottom edges of the inner wall of the body fit, the edges of the flanges abutting against the outer wall of the body. The ends of the sides, *a*, *b*, and the fronts 45 of the dished plates *g*, *h*, form the door opening in the front of the oven. These dished plates are lined with sheet asbestos, and then receive spacers *f'* and are inclosed by cover plates *i*, *k*, the edges of which are 50 bent down as indicated at *i'*, *k'*, to cover over the joints between the body and the top and bottom. Corner plates *l* finish the top, and the feet *m* are located at the corners of the bottom. Tie rods *n* pass through

the cover plate *i*, the dished plates *g*, *h*, the 55 cover plate *k*, and the feet *m*, and have nuts threaded to their lower ends, by means of which the parts of the oven are bound together. These tie rods constitute the only fastening, and by removing them the oven 60 can be completely disassembled. The inner oven walls are free from any kind of a fastening device, and joints are lapped so that no rough edges are left exposed, making it possible to conveniently and thoroughly 65 cleanse the inside of the oven when occasion demands.

The door comprises a frame *r* hinged to the end of one of the sides *b*, the frame comprises a deeply channeled member *s* of rectangular form, having edge flanges, about which the edges of a finished plate *s'* are folded, forming a ledge about the inner margin of the frame, on which the panel *t* of some transparent material, as glass, may be 70 supported, held in place by the angle strips *u* which are secured by the clips *v* which engage the adjacent ends of two of the angle strips. It is desirable to hold the panel securely in place, and the clips engage the 75 angle strips rather than the material of the panel and so avoid damaging it.

The door members of the hinges are formed integrally with the door structure by rolling over the knuckles *s²* from the 80 edge of the channeled member *s*. The door construction is of sheet metal and is very stiff, preventing sagging or warping, and the knuckles formed integrally with the frame make a very rigid hinge support. The 85 pivoted door latch *w* has a slotted end which engages a headed pin *w'* secured in the end of the side wall *a*, and the slotted end is twisted slightly to have a camming action on the pin to cause the door to be tightly 90 shut and its flanges to lie closely against the edges of the door opening to prevent the escape of heat from the interior of the oven.

If desired, a device which I have called a receptor, indicated at *I*, may be used as the 100 direct support for sliding trays, etc., rather than to form ribs on the inner wall of the oven. The receptor, having a closed bottom, catches the drippings and refuse from the cooking, thus keeping the oven floor clean, 105 and may be removed for thorough cleaning, as well as to permit of cleaning the oven.

The floor of the oven is provided with a

central offset portion, raised slightly above the floor which permits the metal to move under expansion and contraction without occasioning the snapping which is objectionable in structures of this sort.

Of course the main body of the oven could be made from more than a single piece of metal, though a small number is preferable. I am also aware that the structure here 10 shown and described is susceptible of modification and change without departing from the spirit of the invention as set forth in the appended claims.

This application is a division of my application serially numbered 783,475 filed 15 August 7, 1913.

I claim as my invention:

1. In a device of the character described, a three-sided, double-walled structure formed 20 from sheet metal bent to shape and constituting the sides and back of the main oven body, double-walled top and bottom members fitted to the top and bottom of the main body, the inner walls of said top and 25 bottom members fitting within the walls of the main body, spacing the said walls from one another, laterally extending flanges on the inner walls of the top and bottom members overlying the space between the walls 30 of the main body member, tie rods at the corners binding said body between said flanges, the front of said oven body being formed by the ends of the sides of the main body and by the edges of the top and bottom members, and a door closing the opening in 35 the front of said oven, hinged to the end of

one of the sides and provided with means for locking it to the end of the other side.

2. An oven, the main body of which, comprising the sides and back, is a spaced 40 double-walled structure formed from sheet metal bent to shape, recessed top and bottom members snugly fitting within the inner walls of the sides and back and with their front edges flush with the ends of the sides, 45 lateral flanges thereon engaging and spacing the walls of the sides and back at top and bottom, cover plates for the top and bottom members, flanges thereon embracing the upper and lower edges of the body, and 50 means for securing said cover plates and body together.

3. An oven, the main body of which, comprising the sides and back, is a spaced 55 double-walled structure formed from sheet metal bent to shape and with its meeting edges secured together, recessed top and bottom members snugly fitting within the inner walls of the sides and back, and with their front edges flush with the ends of the sides, 60 lateral flanges thereon engaging and spacing the walls of the sides and back at top and bottom, cover plates for the top and bottom members, flanges thereon embracing the upper and lower edges of the body, and tie 65 rods at the corners uniting said cover plates and binding said body between them.

FREDERICK E. CARLSON.
